ABSTRACT OF THE DISCLOSURE

A retaining mechanism for slidable doors is described in which pairs of detents are spaced to retain the door in a collapsed condition at each end of its travel as well as fully extended, and in which the detent mechanism includes a spring-loaded plunger having freedom of motion in a direction transverse to the direction of door movement for accommodating misalignment during detent engagement.

This invention relates to a detent mechanism for releasably retaining folding slidable doors at predetermined positions along their path of travel and in a collapsed condition at one end. More particularly, the invention pertains to a retaining mechanism for such doors which is capable of accommodating vertical misalignment between the slidable door and its mounting rails without binding when the doors are moved.

An important problem which is frequently encountered with sliding doors is that of binding or sticking when the door is pulled or pushed out of its normal alignment. This problem is especially acute in the case of collapsing segmented flexible doors, such as shower doors, which are more prone to such misalignment. For such doors, these problems are eliminated through the use of a resilient suspension as described in U.S. Patent No. 3,102,581, Mounting Structure for Slidable Doors, issued to George A. Kochanowski on Sept. 3, 1963. Briefly, this structure comprises a slidable door which is resiliently suspended between rails, whereby when the door is pushed or pulled incorrectly, the forces which would normally cause binding are absorbed, and the door remains on the rails. In prior constructions, the glide members engaging the rails were urged into binding engagement by this motion, but in the Kochanowski mechanism the forces are absorbed by the resilient glide structure, which yields to prevent binding of the glides. When the force tending to cause misalignment is removed, the resilient structure returns the door to its normal position.

It may be seen that this door construction is especially suited to shower stalls as are often constructed in existing bathtub installations by the addition of a shower head and an enclosure. With such installations, it is desirable that the user be able to gain entrance or exit from either end of the tub, thereby requiring that the slidable door be freely movable from one end of its travel to the other, and not be permanently attached to one end of the enclosure. However, in order to maintain an adequate seal against spray and moisture, it is necessary that the door be securely retained at both ends while the shower is in use. Yet when the user wishes to enter or leave the shower, the door must be easily openable from either end, and from both inside and outside of the shower enclosure.

With such slidable doors, it is desirable to provide a means by which the individual panels may be gathered and retained at one end of the travel path. In the case of multi-paneled doors comprising segments of collapsible plastic, the natural resilience of the door segments tends to resist the gathering and forces the door closed unless a positive means of gathering and retaining the

door together is provided. Such a mechanism must be simple, positive in action, and able to accommodate the door misalignment encountered in normal use and accommodated by the previously-mentioned Kochanowski mounting structure.

Previous door retaining devices have not been able to meet these requirements. Mechanical latches have been used, but these generally have the disadvantage of being openable from only one side, making it impossible for a user to actuate the latch if he is standing on the opposite side. Mechanical latches of the conventional door-latch construction are also bulky, and have moving parts which present hard edges and protrusions which are likely to catch the user's clothing. In the case of multi-panel flexible shower doors of the kind contemplated by the present invention, the panels must be maintained under compression when the door is in its folded position, and to accomplish this with a conventional mechanical latch requires an extension of the leading panel which can reach back and behind the collapsed flexible sections to engage the door frame and hold the door in compression. Such a mechanism is beset with all the undesirable features mentioned above.

Another type of door-retaining mechanism utilizes self-attracting magnetic inserts. However, these latches require that the mating surfaces of the door be accurately aligned in order to bring the magnetic inserts into engagement, and the door can be positively retained only in the fully-closed position, and not at some intermediate point. In order to gather the sections of a multi-panel flexible door of the type herein contemplated, a magnetic latch is generally unusable because there is no way by which the leading panel can be retained to the door frame in order to hold the flexible panels in compression.

It is therefore a primary object of the present invention to provide a retaining mechanism for slidable doors which will releasably retain a slidable door in a predetermined position along the path of sliding movement. Another related object is to provide a door-retaining mechanism of the above description for slidable doors which is capable of accommodating misalignment between the door and its rails during operation, while maintaining positive, yet releasable retention force.

Another object is to provide a retaining mechanism of the above description which is capable of retaining the compressed panels of a multi-panel flexible sliding door in a collapsed position at a predetermined location along the path sliding movement.

A further object is to provide a mechanism of the above description which allows a collapsible multi-panel flexible sliding door to be opened from either end of its sliding movement and collapsed into a folded condition at either end of its sliding movement.

A further object is to provide a mechanism of the above description which is simple, sturdy, compact and inexpensive, while being resistant to rust and not requiring the application of oil or grease during service.

Other objects and advantages of the invention will become apparent upon reading the following detailed description and upon reference to the drawings, in which:

FIGURE 1 is a rear elevation of a partly collapsed flexible sliding door assembly such as would be utilized in a bathroom shower stall or bathtub;

FIG. 2 is an enlarged fragmentary section taken in the plane 2—2 of FIGURE 1;

FIG. 3 is a fragmentary section of the latch plunger of FIG. 2 showing displacement during door misalignment;

FIG. 4 is a perspective of the end of a door panel strip, showing the glide mechanism and latch mechanism of the present invention with the cover plate removed;

FIG. 5 is a reduced section taken in the plane 5—5 of FIG. 2, in which the slidable door is illustrated in a

collapsed condition as retained by the mechanism of the present invention; and

FIG. 6 is a perspective of an insert strip as employed in the guide rail of FIG. 5.

While the invention will be described in connection with a preferred embodiment, it will be understood that we do not intend to limit the invention to that embodiment, but intend to cover all alternatives, equivalents and modifications as may be included within the spirit and scope of the invention as defined by the appended claims.

Turning to the drawings, FIG. 1 illustrates a slideable door embodying the retaining mechanism of the present invention. This door is especially suitable for use as a bathtub or shower door, being constructed of multiple panels 10 of flexible plastic material joined to one another by rigid connecting strips 11. Each connecting strip 11 is held in guide rails 12 by glides 13 which are preferably constructed to accommodate lateral misalignment of the door structure to prevent binding and sticking, as with Kochanowski construction previously mentioned. With this door construction, as many flexible panels 10 and door strips 11 are assembled as are needed to fill the space between door frames 15 when the door is in the extended condition. For maximum convenience, the door should be openable from either end. The door may be then simply collapsed accordion-fashion in either direction to enable the user to gain access to the area, shower stall or other enclosure. The flexible panels 10 are folded and collapsed until the individual door strips 11 touch one another, as is best shown in FIG. 5. In this configuration, the door structure is collapsed to its minimum width, and the collapsed door may be slid to either end of the guide rails 12, as the operator desires.

To accomplish these functions, the door is provided with a leading panel strip 16 at each end, and this strip may be provided with a handle (not shown) on each side for convenience in grasping. As a feature of the invention, the retaining mechanism which allows the door to be retained in position is located at the ends of the terminal panel strips, rather than at the center as has often been the practice heretofore. This allows the handle, if provided, to be constructed without provisions for latches, gates, and other mechanical retaining devices. By the elimination of such devices, sharp and protruding edges are avoided and safety to the user is enhanced.

According to the invention, the door is held in the desired position by a captive spring-loaded plunger 17 mounted at the end of each leading panel strip 16 and slideable in top and bottom rail channels 18 in which protrusions or ridges 20 are provided at predetermined locations. Each plunger 17 is resiliently urged outward by a spring 21 into engagement with the adjacent channel 18. Each plunger is preferably retained by a housing 22 so that the limit of its outward extension is just short of contact with the bottom of the adjacent channel 18, while still being sufficient to contact the ridges 20. It may therefore be seen that the channels 18 are interrupted by the ridges 20 to comprise a series of co-linear elongate slots in each of which the plungers 17 may freely ride, while the resilience of the plunger mountings allows the terminal panel strips 16 to ride over the ridges 20 into the next slot if pulled with sufficient force to compress the springs 21.

The ridges 20 are preferably located at the ends of the allowable door travel in both the top and bottom rails so that the door may be latched into position at both ends when extended so as to entirely close the shower enclosure. Alternatively, additional ridges 20 may be provided a short distance from the ends of the door travel (see FIG. 1) to allow the leading panel strips 16 to be selectively retained at some position short of the completely closed configuration. This arrangement allows the door to be collapsed and gathered together at either end of its travel, with the leading panel strip 16 nearest the frame 15 being retained by one pair of ridges, while the other leading

panel strip 16 is retained by an adjoining pair of ridges at the same end as shown in FIG. 5. The door is thus releasably retained in its collapsed position and the resilience of the flexible door panel strips 10 cannot cause the door to spring out.

In carrying out the invention, each plunger 17 is captively retained within its housing 22 and urged outward by a spring 21, as has been described. Taking a single plunger assembly as typical of the others, the outward extension of the plunger is limited by a shoulder 23 on one side of the plunger 17 which engages the housing 22. As an additional feature of the invention, the plunger 17 fits through an opening 25 in the housing 22 that closely embraces the sides of the plunger but is deeper than the plunger thickness. This allows the plunger 17 a limited freedom of movement in the vertical direction in addition to the in-and-out movement accommodated by the spring 21. This has the advantage of allowing the plunger 17 to track correctly in the channel 18 in spite of vertical misalignment of the terminal strips 16 during operation of the door. With a door construction as disclosed by Kochanowski, mentioned previously, each glide 13 has glide rollers 26 which are resiliently supported and allow limited vertical freedom of movement to accommodate misalignment. Therefore, the plunger 17 is similarly shiftable in order to track smoothly and accurately in cooperation with the movement of the resiliently supported glide rollers 26.

As is best shown in FIG. 3, the shoulder 23 is provided on only one side of the plunger 17 and housing 22. On the opposite side of the plunger 17, a beveled surface 27 is provided which allows the plunger 17 to rise and fall as may be necessary to accommodate misalignment of the leading panel strips 16, while retaining resiliency in the in-and-out direction as provided by the spring 21. When the misalignment is relieved, the restoring force of the spring 21 tends to urge the plunger 17 into the position illustrated in FIG. 2, with its shoulder 23 again in engagement with the corresponding surface of the plunger housing 22.

In the preferred construction, the ridges 20 are provided at predetermined locations along the channels 18 in the guide rails 12 by means of a length of strip material 31 in which the ridges 20 are embossed. Because the guide rails 12 are commonly constructed of aluminum extrusions, this construction is facilitated by the provision of an additional slot 32 in the guide rails 12 at the bottom of the groove 18 in which the plunger 17 rides. The ridges 20 may then be located at any desired position along the guide rails 12 by the simple expedient of sliding the strip 31 along the slot 32 until it reaches the desired position. In this way, the door-retaining mechanism of the present invention may be utilized in sliding door installations of any desired length merely by cutting the guide rails 12 to length and inserting a suitably-formed strip 31 into each end.

We claim as our invention:

1. A door assembly comprising, in combination, a rail having a recessed channel, a resiliently collapsible door having opposite ends independently slideable on said rail so that the door can be collapsed at either end of the rail or opened to extend substantially the length of the rail, a resiliently supported plunger mounted at each end of the door adjacent the channel with said plungers being urged into sliding relationship with the channel, and means defining four spaced ridges in said channel against which said plungers are detentably retained, said ridges being disposed in pairs at each end of the channel with one ridge of each pair being positioned at the extreme end of door travel, and the other ridge of each pair being spaced therefrom by a distance not exceeding the collapsed length of said door, whereby the door may be alternately retained in the fully extended, partially extended, or fully collapsed positions at each end of the rail.

2. A door assembly comprising, in combination, a rail member, a slidable door panel member guided by the rail member and retained thereto by glides, said glides being resiliently and movably retained by the door panel member to accommodate misalignment between the door panel member and the rail member, said rail member having a recessed channel aligned along the sliding path of the door panel member and having a retaining ridge positioned therein, a detent plunger housing rigidly carried by the door panel member, and a resiliently supported detent plunger captively retained by the housing for resilient detenting movement against said ridge, said plunger being extendable from the housing through an opening which closely embraces the sides of the plunger and loosely retains the plunger for limited freedom of vertical movement substantially equal to the vertical misalignment accommodated by said resiliently retained

glides, whereby the plunger is enabled to freely follow the channel during misalignment of the door panel and rail members.
